[57] CLAIM

The ornamental design for a soap bar, as shown and described.

DESCRIPTION

FIG. 1 is a perspective view from the top of a soap bar showing my new design;

FIG. 2 is a perspective view from the bottom thereof;

FIG. 3 is a top plan view thereof;

FIG. 4 is a side elevational view thereof;

FIG. 5 is an end elevational view from the right end of FIG. 3;

FIG. 6 is a bottom plan view thereof;

FIG. 7 is a side elevational view thereof from the other side of FIG. 4; and,

FIG. 8 is an end elevational view as seen from the left end of FIG. 3.

FIG. 1

FIG. 2

FIG. 3

FIG. 4

FIG. 5

FIG. 6

FIG. 7
